CLAIM

Int. Filing Date: **Dec. 8, 2015**

The ornamental design for a food package, as shown and
described.

Int. Reg. No.: **DM/091644**

DESCRIPTION

Int. Reg. Date: **Dec. 8, 2015**

1. Food package

Int. Reg. Pub. Date: **Jul. 29, 2016**

1.1 is a front elevational view of a food package with one
tear notch shown in an open position;

(30) **Foreign Application Priority Data**

1.2 is a front elevational view thereof with all tear notches
shown in a closed position;

Jun. 9, 2015 (GR) 20150200068

1.3 is a top plan view thereof with all tear notches shown in
a closed position;

(51) **LOC (11) Cl.** **09-05**

1.4 is a rear elevational view thereof with one tear notch
shown in an open position; and

(52) **U.S. Cl.**

1.5 is a top plan view thereof with one tear notch shown in
an open position.

USPC **D9/714; D9/711**

The broken lines shown are included for the purpose of
illustrating portions of the food package that form no part of
the claimed design.

(58) **Field of Classification Search**

The food package is shown with symbolic breaks in length
in all of the drawing views. It is understood that patentability

USPC D9/416, 519, 643, 702, 707, 711-714,
